UNITED STATES PATENT OFFICE

GWYNN L. LILLARD, OF MEMPHIS, TENNESSEE, ASSIGNOR TO HARNISCHFEGER CORPORATION, OF MILWAUKEE, WISCONSIN, A CORPORATION OF WISCONSIN

MUD SLED

Application filed February 15, 1930. Serial No. 428,616.

This invention relates in general to material handling apparatus and more particularly to handling apparatus of the type embodying a sled or bucket designed for the transportation of earth or other excavated material.

In my copending application, filed October 11, 1929, Serial No. 398,837, there is disclosed an excavating system especially designed and adapted for use in constructing levees. In the excavating system of said application crawler wagons are utilized for transporting the earth from the borrow pit to the levee site. Under many circumstances and conditions these crawler wagons are entirely satisfactory but where the earth that is excavated and transported is wet and of a sticky, muddy or clay-like consistency it may be preferable to utilize a mud sled or sled bucket in lieu of crawler wagons for the purpose of transporting the earth from the borrow pit to the levee site.

The present invention proposes a novel construction of sled bucket and a novel organization of the sled bucket with operating lines, that is, with the haul back and haul in lines of the excavating system of the application above referred to whereby the bucket may be speedily transported from the borrow pit at which it is loaded to the levee site and speedily dumped and returned to the borrow pit under the control and actuation of the haul back and haul in lines.

One of the principal objects of the present invention resides in the feature of utilizing the haul back and haul in lines for the dual purpose of transporting and dumping the bucket. The dumping of the bucket in a speedy and effective manner involves a problem of special difficulty which will perhaps be best appreciated when it is understood that these so-called mud sleds or sled buckets are of very large size and have been constructed with a capacity of twenty-five 45 cubic yards.

Another object of the invention resides in the provision of material handling apparatus having the advantages and capacity mentioned and which is of simple and durable construction, speedy, reliable and effec-

tive in operation and easy and comparatively inexpensive to manufacture.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a diagrammatic view illustrating the sled bucket and its organization with the haul in and haul back lines;

Figure 2 is a view showing the sled bucket in top plan and also illustrating somewhat diagrammatically the connection of the sled bucket to its operating lines;

Figure 3 is a diagrammatic view in side elevation showing the connection of the operating lines to the bucket just prior to the dumping; and

Figure 4 is a view similar to Figure 3 but showing the action of the lines in overturning or dumping the bucket.

Referring to the drawings, and more particularly to Figures 1 and 2, the numeral 1 designates generally a mud sled or sled bucket which is constructed with a bottom 2, side walls 3 and a back wall 5 all suitably connected together and, if desired, suitably reinforced. In the construction illustrated, the marginal portions of the bottom wall and back wall are shown as overlapping the adjacent edges of the side walls. However, the details of the bucket structure may be varied. The top of the bucket is open. As shown in Figure 1, each side wall 3 has its upper edge inclining downwardly toward the front end of the bucket and its lower edge inclining or sloping upwardly adjacent the front end of the bucket. The bottom 2 is also upwardly inclined at the front end of the bucket in a manner corresponding to the upward inclination of the lower edges of the side walls 3, as indicated at 2'.

It will be understood at this point that the sled bucket is used in lieu of the crawler wagon in the excavating system of my copending application above referred to, and is loaded at the borrow pit by means of a

suitable excavating machine, such as a drag-line, power shovel, or the like.

For the purpose of transporting the bucket from the borrow pit to the levee site it is connected up with the haul in line 10 and haul back line 11 operated from the power driven drums 12 and 13. The drums are represented only diagrammatically and they may be and preferably are of the type shown 10 in my copending application Serial No. 398-837. As shown in Figure 2, the haul in line 10 has branches 14 which are secured to suitable connections 15, such as eyes, fixed to the upper rear corners of the bucket, the 15 connections 15 being suitably attached to the side walls 3 and to the overlapping portions of the back wall 5. A spreader bar 16 may be provided between the branches 14 of the haul in line 10. The haul back 20 line 11 is also provided with branches 17 similar to the branches of the haul in line and the branches 17 are secured to connections or eyes 18, the connections 18 being suitably secured to the lower rear corners of the side 25 walls 3 of the bucket. In other words, the connections 15 and 18 are at vertically spaced points on the bucket. A spreader bar 19 may be provided between the branches 17 of the haul back line 11.

30 On the side walls 3 of the bucket adjacent the lower front corners thereof downwardly facing or opening hooks 20 are suitably secured.

When the bucket is to be transported from 35 place to place that is from the borrow pit to the levee site the branches 14 of the haul in line are engaged under the hooks 20 so that the pull of the haul in line is applied to the bucket adjacent the bottom thereof or adjacent the ground. As a consequence the pull 40 of the haul in line does not create any appreciable or material overturning moment and is effective entirely to move the bucket bodily along the ground, the bottom of the 45 bucket sliding over the ground. At the levee site when the bucket is to be dumped the haul in line 10 is slackened and is disengaged from the hooks 20. Then when the haul in line 10 is tensioned or wound up on its drum 50 12, the pull thereof will be applied as shown in Figure 3 with the result that the bucket will be tilted upwardly or overturned to the desired extent as shown in Figure 4 thereby dumping the contents of the bucket over the 55 back of the haul in line. The bucket is righted or turned back to its normal position (shown in Figure 1) by pulling in or tensioning the haul back line. The haul back line 11 is, of course, appropriately tensioned 60 and slackened during the dumping of the bucket.

The invention claimed is:

1. In combination, a mud sled comprising a bottom, side walls connected to the bottom, a 65 back wall connected to said side walls, said

bottom and said side walls inclining upwardly adjacent the forward end of the bucket, a haul in line having branches extending along the side walls of the bucket, connections between said branches and the upper rear 70 corners of the sled, a haul back line having branches, connections between the branches of the haul back line and the lower rear corners of the sled and hooks secured to the bucket at its front lower corners and engageable with the branches of the haul in line to cause the latter to apply its pull along a line parallelizing and close to the base of the bucket.

2. In combination, a sled bucket of suitable construction and having side walls, a haul-in line having branches extending along the side walls, connections between said branches and the upper rear corners of the bucket, a haul-back line having branches, 85 connections between the branches of the haul-back line and the lower rear corners of the bucket, and hooks secured to the bucket at its front lower corners and engageable with the branches of the haul-in line to cause the latter to apply its pull along a line close to the base of the bucket.

In witness whereof, I hereto affix my signature.
